UNITED STATES PATENT OFFICE.

CARL R. KLOK, OF CHICAGO, ILLINOIS, ASSIGNOR, BY MESNE ASSIGNMENTS, TO
UNITED TABLE-BED COMPANY, A CORPORATION OF VIRGINIA.

TABLE-BED.

1,243,424.

Specification of Letters Patent. Patented Oct. 16, 1917.

Application filed December 26, 1913. Serial No. 808,770.

To all whom it may concern:

Be it known that I, CARL R. KLOK, a citizen of the United States of America, and a resident of Chicago, Cook county, Illinois, 5 have invented a certain new and useful Improvement in Table-Beds, of which the following is a specification.

My invention relates to table beds in which the top of the table is necessarily movable 10 in order to permit folding and unfolding of the bed.

The object of my invention is to provide a novel construction and arrangement whereby the top and side and end walls of the 15 table are combined to form a movable cover for the bed, and are detachable from the table body, whereby the weight of said cover is not sustained by the structure when the bed is unfolded for use, and so that the bed 20 when unfolded is not inclosed to any extent by the table.

To these and other useful ends, my invention consists in matters hereinafter set forth and claimed.

25 In the accompanying drawings:—

Figure 1 is a longitudinal section of a table bed embodying the principles of my invention, on line 1—1 in Fig. 2.

Fig. 2 is a transverse section on line 2—2 30 in Fig. 1.

Fig. 3 is an end elevation of said table bed, with one section of the detachable cover removed, and with certain portions of the body shown in section.

35 Fig. 4 is a view similar to Fig. 2, but showing the bed unfolded.

Fig. 5 is an enlarged section on line 5—5 in Fig. 1.

As thus illustrated, my invention comprises a table body A having fixed legs a at the four corners thereof, and having end bars a¹ and side bars a², all rigidly connected together, thereby forming a rigid frame. The top B is hollow or box-like in form and is divided longitudinally of the table to form two similar shaped sections. Each table top section comprises a top wall b and side wall b¹ and end walls b², the said end walls and side walls being adapted to rest on the bars a¹ 45 and a² of the table frame. The edges of the top walls b are adapted to meet tightly at the center of the table, and the edges of the end walls b¹ are adapted to meet in a similar manner at the ends of the table. The 50 table top thus provided has its lower edge 55

equipped with pins C adapted to engage holes in the table body. In this way the table top is held firmly in place.

The folding bed D comprises a rectangular iron frame composed of sections d, d¹ 60 and d², which are pivotally connected together by links d³ and d⁴, whereby the frame is adapted to fold up in the manner shown in Fig. 2. The links d³ are longer than the links d⁴, whereby the section d² is between 65 the section d and d¹ when the bed frame is folded. Moreover, and as shown, this construction provides space for the mattress and bedding, as shown in Fig. 2, whereby the entire bed may be folded into a flat rectangular bundle. The section d is fixed to the 70 table body in any suitable manner, and the other sections are provided with pivoted legs d⁵ and d⁶ connected by long links d⁷ and d⁸ with the links d³ and d⁴, whereby said legs 75 automatically fold and unfold when the bed frame is folded and unfolded.

With this construction, and when the table top is removed and the bed unfolded, there is then no portion of the table which extends 80 above the plane of the bed.

When the bed is unfolded, no portion thereof is inclosed to any extent by the table, and the weight of the table-top is not sustained by the structure, as the top can be detached and entirely removed. The construction shown and described, therefore, affords one way of combining a bed with a table, so that the table is of the ordinary height and proportions, and that the bed will be of the 85 proper height when unfolded. Thus the table has the size and proportions of an ordinary library table, being of a width to pass through an ordinary doorway, and the bed complies with the ordinary or standard 90 requirements as to height and length, and may be of any suitable or desired width, as the table can be made short for a narrow bed, or long for a wide bed, without objectionably varying the proportions thereof. In this 95 way the construction shown and described tends to solve some of the problems involved in the combining of a bed with a table, in one unitary structure, so that the essential requirements of neither one will be sacrificed to the other. Of course, though, I do not limit myself to the exact construction 100 shown and described.

What I claim as my invention is:—

1. A table bed comprising a table body, a 110

5 folding bed frame therein, a removable table top having sides and ends rigidly united therewith, so that no portion of the table top or body extends above the bed when said frame is unfolded, forming a cover for inclosing the bed, means to hold the cover in position on the body, which cover forms no part of the bed frame and is divided into independent and separable sections, the top of 10 the table being without sides and ends other than those of said cover, and legs which are of the proper height for both the table and the bed.

15 2. A table bed comprising a table body, a folding bed frame therein, a removable table top having sides and ends rigidly united therewith, so that no portion of the table top or body extends above the bed when said frame is unfolded, forming a cover for inclosing the bed, means to hold the cover in position on the body, which cover forms no part of the frame and is divided into independent and separable sections, and legs which are of the proper height for both the table and the bed, the division of the cover being in a direction crosswise of the length 40 35 of the bed.

20 3. A table bed comprising a table body, a folding bed frame therein, a removable table top having sides and ends rigidly united 45 50 55

therewith, so that no portion of the table top or body extends above the bed when said frame is unfolded, forming a cover for inclosing the bed, means to hold the cover in position on the body, which cover forms no part of the frame and is divided into independent and separable sections, and legs which are of the proper height for both the table and the bed, the division of the cover being in a direction crosswise of the length 40 of the bed.

4. A table bed comprising a table body, a folding bed frame therein, a removable table top having sides and ends rigidly united therewith, so that no portion of the table top or body extends above the bed when said frame is unfolded, forming a cover for inclosing the bed, means to hold the cover in position on the body, which cover forms no part of the frame and is divided into independent and separable sections, and legs which are of the proper height for both the table and the bed, the division of the cover being in a direction lengthwise of the table.

Signed by me at Chicago, Illinois, this 23rd day of December, 1913.

CARL R. KLOK.
